UNITED STATES PATENT OFFICE.

NED A. OCHILTREE, OF OMAHA, NEBRASKA, ASSIGNOR TO CONCRETE ENGINEERING COMPANY, OF OMAHA, NEBRASKA, A CORPORATION OF NEBRASKA.

ROOFING JOINT.

Application filed April 23, 1928. Serial No. 272,051.

The invention herein disclosed pertains to improvements in sheet metal roofing of either the corrugated or uncorrugated type.

One of the principal objects of the invention is to provide a sheet metal roofing, the individual plates or sheets of which have their edges so arranged and constructed that they may be overlapped with one another to provide a seam or joint which will eliminate leakage and other detrimental effects caused by the capillary action of water, and of such construction that in case water is driven between the edges of the sheet at the joint by the wind or carried therethrough by capillary action, the water will be caught in one or more gutters and prevented from reaching the sheathing or roofing boards.

Another important object is so to form the marginal ends of the sheet that the lap end portions will be noncomplementary, that is, will not conform completely with one another yet similar edges of any two sheets will be complementary so that two or more sheets may be nested for shipping and the like.

Other objects as well as the advantages, functions and uses of the invention will be or should become readily apparent after reading the following description and claims and after viewing the drawing, in which:

Fig. 1 is an end elevation of a portion of a roof showing my joint applied to corrugated sheets,

Fig. 2 is a top plan view of a section thereof, and

Fig. 3 is an edge elevation of a more or less flat metal roofing sheet showing my invention applied thereto.

Referring more particularly to the drawing and for the present to Figs. 1 and 2, a corrugated sheet generally designated 2 has its lapped end shaped to provide a relatively short or small ridge 3, a gutter 4, a relatively high ridge 5, a gutter 6 and a second relatively short or small ridge 7, proceeding toward the edge of the sheet. While the form of the invention illustrated contemplates the formation of the short ridge 7 and the termination or edge of the sheet as at 8 it will be observed that the edge of the sheet may fall anywhere between the ridge 7 and the gutter 6 provided the gutter 6 is retained.

The lapping end of each sheet is provided with a ridge generally designated 9 of sufficient height and breadth to completely span the lapped edge of an adjacent sheet includ-

ing the ridges 3 and 5 and the gutters 4 and 6 and in the illustrated form of the invention the ridge 7 also. The ridge 9 is provided in turn with a smaller ridge 11 adapted to conform to a substantial portion 60 of the transverse width of the crest of the ridge 5 and to seat thereon and while in the illustrated form of the invention the ridge 9 also seats upon and is supported by the outer sides of the ridges 3 and 7, that is, those sides 65 farthest from the center or high ridge 5, it is only essential that its edge 12 or a marginal portion adjacent such edge seat upon and be supported by the outer side of the ridge 3. In other words, if the lapped edge 8 terminates between the crest of the ridge 7 and the gutter 6 the ridge 9 at its inner side will not be supported by the lapped end portion between its ridge 5 and its edge 8.

The construction illustrated in Fig. 3 75 differs from that illustrated in Figs. 1 and 2 only in that the sheet is uncorrugated between its lapping and lapped edges or ends except for a single strengthening rib or ridge 13 which extends substantially parallel to 80 the lapped and lapping ridges of the end portions of the sheet. But in either form of the invention the structure of the joint is the important feature. As will be observed the joints are preferably arranged to fall along a 85 roof board or boards 14 and to be secured thereto by nails or the like 15 which pass through the ridges 11 and 5 into the boards 14, thus providing a very rigid and strong joint which is practically leak proof. Then 90 too, when the sheets are to be shipped they will readily nest with one another when they are assembled with their lapped and lapping end portions respectively together.

Since various modifications and changes 95 may be made in the forms of the invention illustrated and described without departing from the scope and spirit of the invention I do not desire to be limited except by the spirit of the invention and the scope of the appended claims.

I claim:

1. A sheet metal roofing comprising a plurality of metal sheets overlapping one another at their edges, the lapped edge of each sheet 105 having two spaced, short ridges each with depending sloping sides and an intermediate high ridge having downwardly sloping sides joining the inner sides of the short ridges to provide gutters, the lapping edge of each 110

sheet having a single upwardly rising ridge of a width to span both the short ridges and the high ridge of the lapped edge and having a crest portion adapted to seat upon and conform to the top and a relatively small portion only of the sides of the high ridge and to seat upon portions of the outer sides of the short ridges of the lapped edge.

2. A sheet metal roofing comprising a plurality of metal sheets overlapping one another along marginal end portions, the lapped end portion of each sheet being shaped to provide, proceeding toward the edge of the sheet, a relatively short ridge, then a gutter, then a relatively high ridge having a rounded top, then a gutter, the lapping end portion of each sheet being shaped to provide, proceeding toward the edge of the sheet, a transversely curved and upwardly convex ridge of sufficient height and breadth to span said gutters and ridges of the lapped end portion, said lapping ridge having a smaller transversely curved and upwardly convex ridge adapted to conform to and seat upon the crest and upper portions only of the sides of said high ridge of the lapped sheet end.

3. A sheet metal roofing comprising a plurality of metal sheets with overlapping edges, each sheet being formed along the lapped edge with corrugations providing three sub-

stantially parallel ridges, the center ridge being higher than either of the others and a portion of said lapped edge between the center ridge and each shorter ridge lying in substantially the same plane for contact with an underlying support, and along the opposite lapping edge with a single ridge overlapping the said three ridges of an adjacent sheet and receiving support from said three ridges only along the top of the center ridge and the outer sides adjacent the top of each of the smaller ridges.

4. A sheet metal roofing comprising a plurality of metal sheets overlapping one another at their edges, the lapped edge of each sheet having two short rounded top ridges each with downwardly sloping sides and an intermediate high ridge, the lapping edge of each sheet having a single upwardly rounded ridge adapted to span the said three ridges of the lapped edge and having a substantially central portion pressed upwardly to provide a small ridge adapted to seat upon and substantially conform to the top of the center ridge of the lapped edge, the lapping edge being spaced from the lapped edge between the short and high ridges of the lapped edge.

In witness of the foregoing I affix my signature.

NED A. OCHILTREE.
